Bror Walter Svensson, Ostersund, Sweden

Application June 19, 1939, Serial No. 279,790
In Sweden February 22, 1939

2 Claims. (Cl. 280—11.13)

This invention relates to improvements in a ski with one or more longitudinal guiding grooves on its underface, which ski is so designed as to be speedier than those with the ordinary guiding groove or grooves.

Other objects will in part be obvious and in part be pointed out hereinafter.

To the attainment of the aforesaid objects the invention still further resides in those novel details of construction and arrangement of parts, which will be first fully described in the following detailed description and then be pointed out in the appended claims.

According to this improvement the invention is mainly distinguished thereby, that two or more longitudinal recesses are arranged within the side edges of the ski-sole on the line of the guiding groove or grooves and that each recess has such a shape that it at the front in relation to the ski is deeper and of greater width than the guiding groove and that it from this former part gradually decreases to the back part of the ski as well in width as in depth and gradually merges into the groove of the ski.

The accompanying drawing represents by way of an example a form of embodiment of the subject of the invention. Fig. 1 shows the ski from below and Figure 2 the same from the side. Figs. 3 and 4 show on a larger scale cross sections of the ski, taken transverse of the same at places just right in front of these Figures 3 and 4. Figure 5 is a plan elevational view, showing a slight modification of my invention.

The ski 1 shown on the drawing has, as a usual running ski, only one guiding groove 2 but may of course have two or more such grooves parallel to each other. As will be clearly obvious from the drawing the groove at two places has been made wider and deeper, forming recesses 3, which gradually decreases to the back part of the ski as well in width as in depth and at a place 4 merge in the guiding groove. By running and especially by slalom running downhill there will arise small air pockets in these recesses, whereby the friction will be reduced considerably and the speed therefore will be greater than by running with other skis during the

same circumstances otherwise, which matter of fact has been evident by more comparing trials. By running uphill the recesses in usual cases prevents (when the snow is rather tight) perfectly the skis 1 to slide backwards. When the snow is incompact or soft it is sufficient for preventing backwards sliding of the skis by running uphill to put a little ski-paste-oil in the one or both of the recesses.

According to a modification of the invention one or all of the recesses 3 in the ski may however, be of uniform breadth along its whole length but may gradually decrease in depth to the back of the ski, as shown at 4, and gradually merge as well into the grooves 2 as into the gliding surface of the ski.

Having thus described the invention what I claim is:

1. A ski having one or more longitudinal guiding grooves on its underface or gliding sole and two or more longitudinal recesses arranged within the side edges of the ski-sole on the line of the guiding groove or grooves, each recess having such a shape that it at the front in relation to the ski is deeper and of greater width than the guiding groove and that it from this former part is of uniform breadth or width along its whole length but gradually decreases to the back part of the ski in depth and gradually merges as well into the guiding groove as into the gliding surface of the ski.

2. A ski having a central longitudinal guiding groove in its lower surface, said ski being provided with a plurality of intervening longitudinal depressions along its central groove, said depressions being at their forward ends formed with a curved boundary of a width greater than said central groove, and with sides tapering towards the rear ends thereof and merging at their respective ends with said central groove in size and depth, said intervening depressions being deeper at their forward ends than the depth of the central groove, sloping in depth towards the rear ends thereof, substantially as shown and described.

BROR WALTER SVENSSON.
